UNITED STATES PATENT OFFICE.

CHARLES O. ELLERT, OF NEW YORK, N. Y.

MOLD FOR CASTING CONCRETE WALLS WITH A TILE FACING.

1,193,484.

Specification of Letters Patent.

Patented Aug. 1, 1916.

Application filed October 23, 1911, Serial No. 656,224. Renewed December 17, 1915. Serial No. 67,438.

To all whom it may concern:

Be it known that I, CHARLES O. ELLERT, a citizen of the United States, and a resident of the city of New York, borough of Brooklyn, county of Kings, and State of New York, have invented a new and Improved Mold for Casting Concrete Walls with a Tile Facing, of which the following is a full, clear, and exact description.

10 My invention relates generally to molds for plastics and more particularly it is directed to an improvement in a mold construction whereby wall facing elements may be positioned for engagement with the plastic when poured.

15 My invention is especially adapted for use in connection with the mold structure described and claimed in my co-pending application, Serial No. 636,363, filed July 1, 20 1911, renewed Dec. 17, 1915 as Serial No. 67,487.

25 The principal object of my invention is to provide an improved form of mold constructed and arranged to hold wall facing elements in juxtaposition thereto by means of suitable clamping devices, a portion of each device, after the plastic has set and the mold boards have been removed, being left embedded in the wall and serving as a reinforcement thereof.

30 A further object of my invention is to provide an improvement in molds, especially adapted for use in connection with the mold described in my co-pending application hereinbefore mentioned, the mold boards sustaining wall facing elements on their inner sides by means of suitable devices, the plastic being poured between the mold board at the opposite side and the back of the facing 35 elements whereby when the removable securing means between the mold boards and the facing elements is removed and the outer section is taken down, the wall will be faced with the said elements, parts of the securing 40 means being left in the wall as a reinforcement thereof.

45 Other objects and advantages of my invention will appear as the description of the different forms thereof proceeds, all of 50 which are included within the scope of the appended claims.

Reference is to be had to the accompanying drawings forming a part of this specification, in which similar characters of ref-

erence denote corresponding parts in all the views, and in which—

Figure 1 is a side view of my improved mold, portions of the outer boards being broken away in order to show the interior structure; Fig. 2 is a vertical sectional view thereof; Fig. 3 is a vertical sectional view of the finished wall with the mold removed; Fig. 4 is a vertical sectional view showing a different form of mold facing, together with means for securing the parts together; Fig. 5 shows a further modification; Fig. 6 illustrates a structure wherein the facing of the mold is made up of succeeding series of slate; Fig. 7 is a sectional view of a modified form of mold and means for holding the facing thereof in position while the plastic is being poured; Fig. 8 is a perspective view of the holding means shown in Fig. 7; Fig. 9 is a perspective view of one of the elements of the facing used in the structures illustrated in Figs. 1 to 4 inclusive.

As particularly pointed out and claimed in the co-pending application referred to, the mold is made up of standards 1 which 80 extend preferably in a vertical direction, together with a plurality of mold boards 2, there being a plurality of shims or fillers 3 positioned and secured between the mold boards 2 and each of the standards 1; it is 85 to be noted that the width of each shim is equal to that of a form board or a number thereof. Each of the standards is provided with a series of slots 4 through which suitable securing means 5 pass into engagement 90 with the mold boards 2 whereby the mold boards, fillers and standards are firmly and securely held together.

As shown in the drawings, the mold is positioned on top of a part of the finished 95 wall or foundation 100, the lower ends of the standards being secured thereto by means of transversely extending securing means, such as bolts 6, the upper ends of the standards being positioned by means of the 100 longitudinally extending member 7 which is especially adapted to support a number of vertically extending reinforcing rods 8, the member 7 being secured to the standards through the medium of angle irons 9 and 105 bolts or other securing devices 10.

The structure described and claimed in this application is directed particularly to

the combination of the mold boards, and suitable wall facing elements carried thereby; the wall facing elements are secured to the mold boards by suitable means whereby suitable plastic may be poured adjacent the elements; after the plastic has set and the standards, fillers and boards have been removed, the hardened plastic presents a wall with the facing elements secured thereto, portions of the securing means being left in the wall and serving as a reinforcement thereof.

Referring particularly to Fig. 2, the arrangement of the standards 1 and the fillers 3 and mold boards 2 at the right hand side or back of the mold is similar to that set forth in my co-pending application hereinbefore mentioned. The left hand side or front of the mold is made up of the standards 1, together with the fillers 3 and the mold boards 20 with the facing elements 21 carried thereby. The mold boards 20 may be similar to the mold boards 2 at the back of the mold or they may be varied in some details of construction in order to provide for securing the elements 21 to the inner side thereof. As shown particularly in Fig. 2 the height of each of the elements 21 is less than the width of two of the mold boards 20, the difference being provided in order that a longitudinally extending supporting member 22 may be positioned between adjacent ends of facing elements, there being longitudinally extending holding device 23 having shoulders 24 thereon in engagement with the inside of the supporting member and the shoulders 25 present on this form of facing element. The mold is set up in position on top of the foundation or finished wall 100, the left hand side of the mold being the front and the elements 21 are placed adjacent the boards 20 with the supporting member 22 between them, the elements being held in position by suitable securing means, such as bolts 26 which pass through the supporting member and the holding device as well as through the mold boards and preferably between them, the inside of the bolt being provided, if so desired, with a nut 27.

With the parts in the position described the plastic is poured into the mold and when hardened, the mold boards may be removed by first removing the securing devices 5, after which the fillers or shims 3 may be taken out, the removal of these parts permitting the mold boards to be pulled away from the facing elements and entirely removed. The securing devices or fastening means 26 which secure the inner sections in position are also removed, the holding device 23, together with the nuts 27, being left behind in the wall and serving as a reinforcement thereof; the supporting device 22 may also be removed, the finished

appearance of the wall being as set forth in Fig. 3 where the elements 21 are shown secured in position and adhering to the hardened material of the wall. The supporting device 23 may be made of any suitable material and in the event that the facing elements 21 are made of tile or similar substance, these supporting members will preferably be made of the same material so that in the finished wall structure the facing will be uniform throughout. Of course the openings or holes left in the holding device 23 and through which the securing or fastening bolts 26 pass may be subsequently filled up. One of these elements 21 is set forth particularly in Fig. 9; it is there shown provided with a series of horizontally extending grooves 30 and spaced vertically extending grooves 31 in order to give the appearance of a brick structure, although it is obvious that the outer face of each of these elements may be provided with any suitable design whereby different forms and sizes are provided.

In Fig. 4 I have illustrated a mold somewhat similar to that shown in Fig. 2, the modification residing in the fact that each of the facing elements 21' are of the same height or width as the mold boards 30, such an arrangement presenting a finished wall structure wherein the elements 21' thereof are closely adjacent with no removed portions or channels between them, such as is shown in Fig. 3; securing or fastening devices 26 may be used in this structure, these devices passing between the shoulders 25' of adjacent elements the inner end of the fastening or securing device being in engagement with a block 23' whereby adjacent sections are securely held in place. In the use of this form of mold, the blocks 23' and the nuts 27 on the inner end of the securing device 26 are left in the wall as a horizontal reinforcement thereof when the mold boards together with the standards and fillers are removed.

In Fig. 5 the facing elements are made up of a series of bricks 21^a suitably positioned with respect to one another, and held adjacent the mold boards 20 by the securing means 26 which are clamps or equivalent devices similar to that already described, the inner end of the securing means being provided with a transversely extending bar 23^a which is of sufficient length to engage a number of the bricks or tile so that they will be held secured in position when the plastic is being poured into the mold. Of course these transversely extending bars 23^a and the nuts or equivalent devices 27 on the inside of the fastening means 26 are left in the finished wall serving as a reinforcing means thereof, when the form boards are removed, the finished wall in this case presenting an outer facing which is made up of a number of 130

bricks or tiles of suitable design and of any convenient dimensions.

In some cases it may be desirable to have the finished wall faced with slate, successive 5 rows of which are arranged in clapboard fashion and to this end I have illustrated means in Fig. 6 whereby such may be obtained. The mold boards 20 have suitable blocks 20^a positioned between them, each of 10 these blocks being provided with an inner and preferably rubber-faced shoulder 40 against the top of which the facing elements 23^b are adapted to rest, being secured in such position by engagement with the upper end 15 23^c of an adjacent element 23^b, there being a fastening device 26 similar to that already described passing through the block 20^a and the upper end 23^c of the element 23^b and having a nut or equivalent element 27 secured 20 to its inner end, whereby the parts are held together. In order to provide for sufficient engagement of the elements 23^b and the plastic I provide each of the elements with an inwardly extending hook 41 whereby they 25 become firmly bonded. It is to be particularly noted that by using the shoulder 40 at the inner end of the blocks 20^a, which shoulder is preferably of width equal to the thickness of each of the elements 23^b, I provide 30 a system of over-lapping units whereby the face of the finished wall is made up of over-lapping elements, such as slate or tile. In this structure the removal of the outer sections 20 and the fastening devices 26, together 35 with the blocks 20^a through which these fastening devices pass, leaves the finished face surface of the wall, the opening or holes therein through which the fastening devices pass being subsequently filled up 40 with any suitable cement or plastic.

In Figs. 7 and 8 I have shown a modified form of means for holding the facing elements in position which in some respects is much simpler than those previously described inasmuch as the number of parts required for normal operation thereof is lessened. The left hand side of the mold is made up of the mold boards 20, similar to those described in my co-pending application hereinbefore referred to, the facing elements being made up of a series of vertically extending tiles of simple rectangular formation of any desirable material and outline, as well as size. These elements are placed 50 one above the other closely adjacent the inside of the mold boards 20 and are held in such position by the following means. Secured adjacent the top of the mold is a longitudinally extending member 50 having a series of vertically extending openings therein through which wire members are rotatably mounted, each member being made up of the vertically extending portion 51 and the horizontally extending portion 52, the 55 inner ends of the portions 52 being connect-

ed to a rod 53; suitably positioned along the member 50 are blocks 54 having openings therein across which a pin 55 extends, each of these pins being adapted to be engaged by a hook 56 which passes through the mold 70 boards 20 whereby the parts are firmly held in position, as shown in Fig. 7. The distance between the vertically extending portions 51 and the inside of the mold boards 20 is substantially equal to the thickness of the 75 elements 21^b so that these portions 51 bear against these elements with a certain pressure, whereby they are held in position. As the plastic is poured into the mold and begins to harden, the rod 53 may be moved 80 back and forth, thereby rotating the portions 51 within the plastic so that they will not adhere thereto in the hardening process; when the plastic has been sufficiently tamped or set to support the inner sections of the 85 mold boards, the member 50 may be lifted, and with it the portions 51 and 52, and may be placed in position at a higher point in the mold, ready to engage the elements 21^b which may then be added and placed in position before any more plastic is poured. As the wall increases in height this holding means for the inner sections is moved 90 with it and when the wall is finished it may be entirely removed therefrom; the standards, and mold boards, together with the fillers, may be then removed and the finished wall has the facing elements secured thereto, there being no openings left in the facing or between any of the elements which 95 go to make up the facing.

Of course the wires or rods 51 may be left embedded in the concrete and the member 50, or a number of such members, may be used to space and hold the rods or wires in 100 position; the member 50 may be lifted when so desired, the rods 51 slipping through the openings therein, such a method leaving the rods or wires as a reinforcement within the 105 finished wall.

From the above description taken in connection with the accompanying drawings it will be seen that I have provided a structure and several modifications thereof, any one of which is well adapted to perform the 110 objects of the invention as stated in the beginning of this specification; the size of the mold and the material of which the various parts are made may be widely varied, depending on the use to which the finished 115 structure is to be put, such changes and modifications being included within the spirit and scope of the appended claims.

Having thus described my invention, I claim as new, and desire to secure by Letters 120 Patent:—

1. A tile element mold comprising spaced uprights; mold walls supported by said uprights; and a tile or wall facing supporting means, said means including a plurality of 125

- elements adapted to detachably engage one of said mold walls, and a plurality of elements adapted to engage said first elements and the rear faces of said tiles or wall facing.
2. A tile element mold having a plurality of facing elements or tiles adjacent the inner faces of mold sections in a mold wall of said mold; holding means in engagement with the rear faces of said tile elements; and a plurality of removable means passing through said mold wall and said holding means to position said tile or facing elements.
3. In combination, a tile element mold comprising spaced uprights; mold sections supported by said uprights; facing elements adjacent the inner faces of said mold sections; holding devices adjacent the rear faces of said facing elements, together with

means passing through said holding devices and the mold sections whereby the facing elements are detachably positioned.

4. In combination, a tile element mold comprising spaced uprights, mold sections supported by said uprights; a plurality of facing elements adjacent the inner faces of said mold sections; longitudinally extending holding means engaging the rear faces of said facing elements; and removable securing means engaging said holding means and said mold sections.

In testimony whereof I have signed my name to this specification in the presence of two subscribing witnesses.
